CLAIM

The ornamental design for a toy opossum animal figure,
as shown and described.

DESCRIPTION

FIG. 1 is a front perspective of a toy opossum animal
figure showing my new design;

FIG. 2 is a top plan view thereof;

FIG. 3 is a left side elevation, the right side being a
mirror image thereof;

FIG. 4 is a front elevation thereof;

FIG. 5 is a rear elevation thereof;

FIG. 6 is a bottom plan view thereof; and

FIG. 7 is a bottom plan view of a second embodiment
thereof, the other views being the same as in FIGS. 1-5.
